[57] CLAIM

The ornamental design for a wrapping sheet for magnetic tape cassette, substantially as shown and described.

DESCRIPTION

FIG. 1 is a plan view of a wrapping sheet for magnetic tape cassette showing my new design;

FIG. 2 is a top or bottom edge view thereof;

FIG. 3 is a side edge view thereof; and

FIG. 4 is an isometric view showing the wrapping sheet wrapped around a magnetic tape cassette.

FIG. 1

FIG. 2

FIG. 3

FIG. 4
